IRONING MACHINE

Wallace F. Oliver, Detroit, Mich., assignor to
 Hydraulic Brake Company, Detroit, Mich., a
 corporation of California

Application November 12, 1934, Serial No. 752,727

10 Claims. (Cl. 68—9)

This invention relates to ironing machines and more particularly to ironing machines for domestic use.

Broadly the invention comprehends an ironing machine including cooperative ironing elements, one movable into and from operative position by actuating means including means for locking this element in any one of a plurality of operative positions, and the other movable by hydraulic means to create an ironing pressure between the elements.

An object of the invention is to provide an ironing machine having relatively movable ironing elements and means for retaining one of the elements in any one of a plurality of operative positions.

Another object of the invention is to provide an ironing machine having relatively movable ironing elements, one manually movable into any one of a plurality of operative positions and there retained against movement, and the other movable by hydraulic means having actuating means controlling the retaining means.

Another object of the invention is to provide an ironing machine having relatively movable ironing elements, one movable into and from any one of a plurality of operative positions by force applied to a foot pedal lever, means for retaining this element in any one of a plurality of positions, and the other element movable by a fluid pressure system including a compressor and means for actuating the compressor including means for releasing the retaining means.

Other objects of the invention will appear from the following description taken in connection with the drawings which form a part of this specification, and in which,—

Figure 1 is a cross sectional view of an ironing machine embodying the invention;

40 Figure 2 is an enlarged fragmentary view illustrating the mechanism for actuating the head and for locking the head in operative position;

Figure 3 is a sectional view substantially on line 3—3, Figure 1;

45 Figure 4 is a sectional view substantially on line 4—4, Figure 1;

Figure 5 is a detail view of a locking device;

Figure 6 is a top plan view of the buck support;

50 Figure 7 is a longitudinal sectional view of the buck support illustrating the arrangement of the fluid pressure motors and the buck actuated thereby;

55 Figure 8 is an enlarged detail view of one of the fluid pressure motors;

Figure 9 is a top plan view of a fluid compressor for actuating the buck;

Figure 10 is a vertical sectional view substantially on line 10—10, Figure 9;

Figure 11 is a sectional view substantially on line 11—11, Figure 9;

Figure 12 is a sectional view substantially on line 12—12, Figure 9; and

Figure 13 is a diagram of the electrical circuit for the machine.

Referring to the drawings for more specific details of the invention, 10 represents a frame having a sump 12 at one end and a hollow upwardly extending column 14 at its other end. The upper end of the column 14 terminates in a spherical portion 16, the object of which will hereinafter appear.

The frame is supported by a column 18 fitted in a sleeve 20 suitably secured to the frame concentric to the column 14, and corresponding legs 20 22 secured respectively to the respective sides of the frame.

A top 24 supported by the frame has openings for the reception of the column 14 and an upwardly extending frustro-conical portion 26 25 having an opening 28 registering with the sump 12. The top also has an apron 30 which together with a shield 32, suitably secured to the frame, effectively conceal from view the operating mechanism of the machine.

30 A fluid compression device indicated generally at 34 is suitably mounted in the sump 12. This device includes a reservoir 36 having a cover 38 provided with a concentric opening. The cover is suitably secured against displacement as by a retaining ring 40. A reciprocal piston 42 in the reservoir has a concentric sleeve extending through the head of the piston. A leak-proof cup 44 on the head of the piston is retained against displacement by a circumferential flange 46 on the sleeve, and a hollow rod 48 threaded in the sleeve extends through an opening in the cover of the reservoir and is provided with a closure plug 50. A spring 52 interposed between the cover 38 of the reservoir and the back of the piston 42 urges the piston toward the bottom of the reservoir to impose pressure on the fluid therein. By removing the plug 50 and retracting the piston, the reservoir may be filled through the rod 48.

50 Formed in the base of the reservoir is a compound cylinder 54 including a large cylinder 56 and a small cylinder 58 arranged coaxially and communicating with one another. The large cylinder 56 has ports 60 and 62 providing communications between the large cylinder and the reser- 55

voir, and the small cylinder has a discharge port 64 controlled as by a check valve 66.

A reciprocal piston 68 in the compound cylinder 54 is held against displacement by a retaining ring 70 fitted in a groove in the wall of the cylinder 56 adjacent the open end thereof. This piston has heads 72 and 74 spaced apart by a sleeve 76, and a skirt provided with spaced radial flanges 78 between which is fitted a leak-proof cup 80. 10 A portion of the skirt is reduced in diameter to provide in conjunction with the wall of the cylinder an annular chamber 82 communicating with the reservoir 36 as by way of the port 60.

The head 72 is fitted in the larger cylinder 56 15 and has a plurality of ports 84 providing communications between the annular chamber 82 and that portion of the cylinder 56 forward of the head 72. A collapsible leak-proof cup 86 loosely fitted in a circumferential groove in the 20 piston controls the ports 84. This cup is normally held against the head by a relatively light spring 88 interposed between the cup and a suitable stop 90.

A plug 92 suitably secured in the skirt of the 25 piston provides, in conjunction with the skirt, a chamber 94 communicating with the sleeve 76. The chamber 94 has a port 96 providing a communication between the chamber 94 and the annular chamber 82, and a plurality of ports 98 30 providing communications between the chamber 94 and that portion of the cylinder 56 forward of the piston 72.

The head 74 of the piston is fitted in the smaller cylinder 58. This head has a plurality of ports 100 35 providing communications between the larger cylinder 56 and the smaller cylinder 58. This head also has an extension 102 having a passage 104 providing a communication between the sleeve 76 and the smaller cylinder 58. A collapsible leak-proof cup 106 on the head 74 of the piston is retained against displacement by a flange 108 on the extension 102, and interposed 40 between the flange 108 and the head of the smaller cylinder 58 is a spring 110 for urging the piston to its retracted position.

A reciprocal piston 112 in the sleeve 76 has on its head a leak-proof cup 114 held against displacement by a spring 116 interposed between the cup and the back of the piston 74. The piston 112 carries a valve 118 urged by a relatively heavy spring 120 to a cushioned seat 122 in the chamber 94 to close the ports 98.

A recess 124 in the plug 92 in the skirt of the piston receives one end of a thrust rod 126, the 55 other end of which is pivotally attached to an arm 128 keyed to a shaft 130 journaled in a suitable bearing 132 on the frame, and an operating lever 134 suitably secured to the shaft 130 has an extension 136, and threaded on the extension is a 60 knob or hand grip 138 easily accessible to an operator. Upon applying force to the lever 134 the shaft 130 may be moved through an angle and this movement is transmitted through the arm 128 and the thrust pin 126 to move the piston 65 68 on its compression stroke.

A valve chamber 140 formed in the base of the reservoir 36 has a port 142, providing a communication between the valve chamber and the reservoir, and a port 144 the object of which will 70 hereinafter appear. A valve cage 146 fitted in the valve chamber is secured in place by a plug 148 threaded in the open end of the chamber. The valve cage has a circumferential groove 150 75 communicating with the ports 142, and a port 152 providing communication between the groove 150

and the interior of the cage. The cage also has a head 154 located between the ports 142 and 144, and the head has a concentric port 156.

A leak-proof cup 158 on the head of the valve cage has a concentric opening and the perimeter defining this opening overhangs the perimeter defining the port 156. Another leak-proof cup 160 is seated on the head of the valve chamber, and a spring interposed between the cups 150 and 160 effectively retains the cups against displacement. 10

A valve 164 has a portion 166 adapted to enter the port 156 in the head of the valve cage and engage the overhanging perimeter of the leak-proof cup to effectively seal the valve when it is 15 in closed position. The valve has a stem 168 extending through the head of the valve chamber. An adjustable collar 170 on the valve stem and a spring 172 sleeved on the stem between the collar and the head of the valve chamber urges the 20 valve to its closed position. The free end of the valve stem abuts a screw 174 adjustably mounted in an arm 176 keyed on the shaft 130 journaled on the frame 10.

The arm 176 has an offset portion or driver 25 178, the object of which will hereinafter appear, and a notch 180 for the reception of a spring-pressed plunger 182 suitably mounted on the frame 10. When the plunger 182 is in engagement with the notch 180, the operating lever 134 30 is retained in neutral position.

A buck support suitably mounted on the reservoir 36 includes an elongated receptacle. Fluid pressure motors 186 and 188 are mounted respectively in the respective ends of this receptacle. 35 Each of these motors includes a cylinder 190 having therein a reciprocal piston 192. The piston is provided with a head 194 having an extension 196 on which is fitted a leak-proof cup 198, and the extension 196 has a diametral bore 40 200 communicating with an axial bore 202 in the piston. A bleeder screw 204 is threaded in the bore 202 in the piston, and fitted on the back of the piston is a cap 206 enclosing the bleeder screw. 45

The cylinders of the fluid pressure motors 186 and 188 are connected respectively by conduits 208 and 210 to a coupling 212. The coupling is connected by a conduit 214 to the discharge port of the compressor, with the valve 66 interposed, 50 and by a conduit 216 to the port 144 in the valve chamber 140.

A buck 218 of any preferred type has on its back a flange 220 arranged to partially telescope the receptacle 184, and pressure plates 222 bearing 55 against the caps 206 on the respective pistons 192. The buck also has formed on its back adjacent its respective ends corresponding sleeves 224 embraced by suitable guides 226 on the walls of the cylinders of the respective fluid pressure motors 60 186 and 188. Rods 228 suitably secured in the bottom of the receptacle 184 extend upwardly into the sleeve 224. The rods have heads, and sleeved on the rods between their heads and retaining rings in the open ends of the sleeves are 65 coil springs 230.

An ironing head 232 adaptable for cooperation with the buck 218 is pivotally connected to corresponding oppositely disposed horns 234 formed on one end of a hollow arm 236, the other end of 70 which is flared as indicated at 238 to receive the spherical portion 16 on the column 14. The arm 236 has an internal web 240. This web has an integral arm 242 which extends downward into the column 14 and is pivoted to the spherical por- 75

tion 16 of the column 14. A yoke 244 pivoted on the arm 242 is connected by coil springs 246 to adjusting screws 248 suitably mounted on the frame. Upon completion of an ironing operation 5 the springs 246 function to actuate the arm 236 to move the head 232 to the elevated or inoperative position.

A segment 250 pivoted on the frame is connected by a link 252 to the end of the arm 242. 10 This segment has a ratchet 254 arranged for cooperation with a spring-pressed pawl 256 pivoted on the sump 12, and the pawl carries an adjusting screw 258 arranged for cooperation with the driver 178 on the arm 176. When the head 232 15 is moved into operative position, the segment is moved to a position where the ratchet thereon may be engaged by the pawl to lock the head against movement.

In some instances it may be found desirable to 20 lock the head in any one of a plurality of positions wherein the head does not engage the buck. This is highly desirable when the ironing head 232 is equipped with attachments for ironing ruffles and other articles. Such an ironing head is fully disclosed in the application of Otto C. Lang, Serial 25 No. 717,499, filed April 11, 1934. Accordingly, the segment 250 is provided with an aperture arranged for the reception of a plunger 260. This plunger is retained in disengaged position by a 30 spring 262. A member 264 pivoted on a bracket 266 on the frame engages the plunger, and a rod 268 having a portion threaded in the bracket engages the member 264. By manipulating the rod the member 264 is moved through an angle 35 and this movement is transmitted to the plunger 260 to engage the plunger in the apertures in the segment 250 to lock the head against movement.

A foot pedal lever 270 suitably mounted in the column 18 is connected by a two-part rod 272 to 40 the arm 244. The rod extends through a bracket, and sleeved on the rod between the bracket and a collar 274 on the rod is a coil spring 276. Because of the two-part rod structure, the machine may be disassembled without the necessity 45 of disconnecting the rod.

By depressing the pedal 270, force is transmitted through the rod 272 to the arm 242 causing the arm to move on its pivot resulting in movement of the head 232 into operative position. 50 A fluid pressure switch 278 connected in the coupling 212 is connected in a circuit 280 including a lamp 282 housed in the arm 236 adjacent an opening in the arm having therein a colored glass 284. The circuit 280 is tapped off 55 of a circuit 286 including a heating element 288 arranged within the ironing head, and a rheostat 290 arranged on the top of the ironing head. The circuit 286 may be connected to any suitable source of electrical supply.

60 In operation, assuming that the fluid pressure system is filled with fluid, that the circuit 284 is connected to a suitable source of electrical supply, that the head 232 is in elevated or inoperative position, and that the buck is in lowered position or the position of rest wherein the pistons of the fluid pressure motors 186 and 188 are in retracted position with the buck held against the pistons by the springs 230,—under these conditions, the operator places the work 65 upon the buck and depresses the foot pedal lever 270, resulting in lowering the head into operative position, which position varies according to the thickness of the work.

Upon moving the head into operative position 70 75 the arm 242 is moved through an angle, and this

movement of the arm places the springs 246 under tension and transmits force through the link 252 to the segment 250, resulting in moving the segment into position for engagement of the ratchet 254 thereon with the pawl 256. 5

After moving the head into operative position, the operator depresses the lever 134, whereupon the operating shaft 130 is moved through an angle. Upon the initial movement of this shaft, the arm 128 on the shaft transmits force through 10 the thrust pin 126 to move the piston 68 on its compression stroke, and the arm 178 keyed to the shaft is moved to disengage the plunger 182 from the retaining notch 180 in the arm 176, and simultaneously therewith the driver 178 on the arm 15 176 is moved to disengage the spring-actuated pawl with the result that the pawl moves into engagement with the ratchet 254 on the segment 250 and locks the segment against movement, and since the segment is connected by the link 252 20 to the arm 242 and this arm is integral with the arm 236 and the horns 234 supporting the head, the head is locked in operative position.

During the initial movement of the piston 68 on its compression stroke, the leak-proof cup 86 25 covers the port 62, and the fluid in the larger cylinder 56 is displaced through the port 100 in the head 74, past the leak-proof cup 106 into the smaller cylinder 58, thence through the discharge port 64, past the check valve 66, through 30 the conduit 214, coupling 212 and conduits 208 and 210 to the fluid pressure motors 186 and 188, resulting in actuating the pistons 192 of the fluid pressure motors against the resistance of the springs 230 and movement of the buck 218 against 35 the head 232.

This movement of the buck 218 is the result of the displacement of fluid due to the initial movement of the piston 68, and upon further movement of the piston 68 a predetermined pressure 40 45 is obtained, whereupon the piston 112 is actuated by the fluid under pressure in the cylinder 56, resulting in tripping the valve 118 which renders the piston head 72 ineffective for producing pressure, the fluid forward of the head 72 being returned to the reservoir 26 by way of port 98, chamber 96, port 96, annular chamber 82, and port 60. As the piston proceeds on its compression stroke the fluid under pressure in the smaller cylinder 58 operates against the piston 112 to 50 retain the valve 118 in open position.

This transition of pressure occurs over a relatively wide range dependent entirely upon the relation of the area of the piston 112 to the area of the valve 118. Because of the restricted opening 98 providing communication between the cylinder 56 and the face of the valve 118, sudden movement of the piston 68 on its compression stroke will not cause actuation of the valve 118. 55

When the pressure between the ironing elements has reached a predetermined degree, the fluid under pressure in the system actuates the fluid pressure switch 278 to close the circuit 280, resulting in lighting the lamp 282, which gives a visual indication that the required pressure between the head and the buck to effectively iron the work has been obtained. 60 65

Upon release of the lever 124 the check valve 66 closes, and maintains the pressure at a predetermined degree. After maintaining the pressure for sufficient time to effectively iron the work, the operator releases the lever 134. In this operation, upon the initial movement of the lever, the shaft 130 is rocked, and this movement of the shaft is transmitted through the arm 128 70 75

to the thrust pin 126 resulting in retracting the thrust pin. As the thrust pin is retracted the piston 68 is returned under the influence of the spring 160 to its retracted position.

- 5 As the piston 68 returns to its retracted position, the cups 86 and 106 collapse, and fluid is drawn from the reservoir 36 through port 60, annular chamber 82, ports 84, past the cup 86, into the larger cylinder 56 forward of the piston 10, thence through ports 100, past cup 106, into the smaller cylinder 58, filling the cylinders 56 and 58 for subsequent operations.

Further movement of the lever toward neutral position transmits force through the arm 176 on the shaft to the valve stem 168, resulting in tripping the valve 164, whereupon the pressure on the fluid in the fluid pressure motors 186 and 188 is released, and fluid is returned from these motors through the conduits 208 and 210, coupling 212 and conduit 216 to the valve chamber 140, past the valve therein, and thence through port 142 to the reservoir 36. This flow of fluid is due to the tension on the springs 230 connected between the buck 218 and the buck support 184.

As the operating lever 134 approaches neutral position, the driver 178 on the arm 176 actuates the pawl 256 to disengage the pawl from the ratchet 254 on the segment 250. Upon disengaging the pawl from the ratchet, the springs 248 become effective to return the head 232 to elevated position, and upon the operating lever moving into neutral position the plunger 182 engages the notch 180 in the arm 176 and thereby retains the operating lever in neutral position and at the same time retains the valve 152 in open position.

Although this invention has been described in connection with certain specific embodiments, the principles involved are susceptible of numerous other applications that will readily occur to persons skilled in the art. The invention is, therefore, to be limited only by the scope of the appended claims.

45 Having thus described the various features of the invention, what I claim as new and desire to secure by Letters Patent is,—

1. An ironing machine comprising cooperative ironing elements, means for moving one of the elements into operative position, a ratchet connected to this element, a pawl cooperating with the ratchet for retaining this element in operative position, means for actuating the other element to create an ironing pressure between the elements, and means for operating the actuating means including means for tripping the pawl upon completion of the ironing operation.

2. An ironing machine comprising cooperative ironing elements, one of the elements mounted to swing into and from operative position, a ratchet connected to the swinging element, a pawl cooperating with the ratchet for retaining the swinging element in operative position, means for actuating the other element to create an ironing pressure between the elements, means for operating the actuating means including means for disengaging the pawl from the ratchet upon completion of the ironing operation, and means for moving the swinging element from operative position upon disengaging the pawl from the ratchet.

75 3. An ironing machine comprising cooperative ironing elements, one mounted to swing into and from operative position a lever for actuating the swinging element into operative position, a

spring for moving the swinging element from operative position, a ratchet connected to the swinging element, a pawl cooperating with the ratchet for retaining the swinging element in operative position, means for actuating the other element to create an ironing pressure between the elements, and means for operating the actuating means including means for tripping the pawl upon completion of the ironing operation.

4. An ironing machine comprising cooperative ironing elements, a foot pedal lever for moving one of the elements into operative position, a spring for moving this element from operative position, a ratchet segment connected to this element for concomitant movement therewith, a spring-pressed pawl pivoted on a fixed support and arranged for cooperation with the ratchet segment, means for actuating the other element to create an ironing pressure between the elements, means for operating the actuating means including means for disengaging the pawl from the ratchet segment upon completion of the ironing operation.

5. An ironing machine comprising an ironing head and a buck for cooperation therewith, a member supporting the head for movement into and from operative position, a foot pedal lever for actuating the member to move the head into operative position, a ratchet connected to the member, a pawl pivoted on a fixed support and arranged for cooperation with the ratchet for retaining the head in operative position, tension means cooperating with the member for moving the head from operative position, means for actuating the buck into pressing engagement with the head, and manually operative means for operating the actuating means including means for tripping the pawl upon completion of the pressing operation.

6. An ironing machine comprising a frame, a buck on the frame, an ironing head, an arm on the frame supporting the head for movement into and from operative position, a foot pedal lever for actuating the arm to move the head into operative position, means for retaining the head in operative position including a ratchet segment pivoted on the frame and connected by a link to the arm, a pawl pivoted on the frame and arranged for cooperation with the ratchet segment, means for actuating the buck into pressing engagement with the head, and means for operating the actuating means including means for disengaging the pawl from the ratchet upon completion of the pressing operation.

7. An ironing machine comprising a frame, a buck on the frame, an ironing head, means on the frame supporting the head for movement into and from operative position, a ratchet segment pivoted on the frame and connected to and movable concomitantly with the supporting means, a pawl pivoted on the frame and arranged for cooperation with the ratchet segment, means for actuating the supporting means to move the head into inoperative position, means for actuating the buck into pressing engagement with the head, and a means for operating the actuating means including means for disengaging the pawl from the ratchet upon completion of the pressing operation.

8. An ironing machine comprising a frame, a movable support thereon, an ironing head on the support, a buck on the frame for cooperation with the ironing head, a lever connected to the support for actuating the support to move the

- head into operative position, a ratchet segment pivoted on the frame, a link connecting the ratchet segment to the support, a spring-pressed pawl on the frame for cooperation with the ratchet segment, means tending to move the head from operative position, means for actuating the buck into pressing engagement with the head, means for operating the actuating means including means for disengaging the pawl from the ratchet segment upon completion of the pressing operation.
9. An ironing machine comprising a head, a buck for cooperation therewith, means supporting the head for movement into and from operative position, means tending to move the head from operative position, means for retaining the head in any one of a plurality of operative positions including a ratchet connected to and movable concomitantly with the head and a pawl cooperating with the ratchet, means for actuating the buck into pressing engagement with the
- head, and means for operating the buck actuating means including means for disengaging the pawl from the ratchet upon completion of the pressing operation.
10. An ironing machine comprising a head, a buck for cooperation therewith, means supporting the head for movement into and from operative position, a lever for actuating the supporting means to move the head into operative position, means tending to move the head from operative position, means for retaining the ironing element in any one of a plurality of operative positions including a ratchet connected to and movable concomitantly with the supporting means and a pawl cooperating with the ratchet, means for actuating the buck into pressing engagement with the head, and means for operating the buck actuating means including means for disengaging the pawl from the ratchet upon completion of the pressing operation.

WALLACE F. OLIVER.
